(57) **CLAIM**

The ornamental design for a photography stick, as shown and described.

DESCRIPTION

FIG. 1 is a front, right and top perspective view of a photography stick, showing my new design;

FIG. 2 is a rear, left and bottom perspective view thereof;

FIG. 3 is a front, right and top perspective view, shown in a folded state;

FIG. 4 is a rear, right and top perspective view, shown in a folded state;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is an enlarged view of portion of FIG. 1 thereof;

FIG. 12 is an enlarged view of portion of FIG. 1 thereof;

FIG. 13 is an enlarged view of portion of FIG. 2 thereof;

FIG. 14 is an enlarged view of portion of FIG. 2 thereof; and, FIG. 15 is a perspective view shown separated for an ease of understanding.

The evenly spaced dash-dash broken lines shown in the drawings illustrate portions of the photography stick that form no part of the claimed design. The dash-dot-dash broken lines shown in the drawings illustrates areas of enlargement that form no part of the claimed design.

1 Claim, 15 Drawing Sheets
